CLAIM

An ornamental design for a ball cap having indicia comprising a baseball skin, as shown and described.

DESCRIPTION

FIG. 1 is a front, right perspective view of the ball cap;

FIG. 2 is front view of the ball cap;

FIG. 3 is a left side view of the ball cap;

FIG. 4 is a right side view of the ball cap; and,

FIG. 5 is a top view of the ball cap.

A characteristic feature of the design resides in the indicia on the front of the cap that comprises a baseball skin and the texture thereof.
